CARBURETER.

1,018,164.

Specification of Letters Patent. Patented Feb. 20, 1912.

Application filed January 7, 1911. Serial No. 601,414.

To all whom it may concern:

Be it known that we, FRANCIS A. CHAPIN and WILLIAM Y. CHAPIN, of Indianapolis, county of Marion, and Muncie, county of 5 Delaware, respectively, State of Indiana, have invented a certain useful Carbureter; and we do hereby declare that the following is a full, clear, and exact description thereof, reference being had to the accompanying 10 drawings.

The object of our invention is to provide improvements in carbureters so as to form a better admixture of air and hydro-carbon to form gas.

15 The features of the invention will be understood from the accompanying drawings and the following description and claims:

In the drawings Figure 1 is a side elevation of the carbureter. Fig. 2 is a plan view showing the device in idle position. Fig. 3 is a plan view showing the position of parts at high speed. Fig. 4 is a central vertical section through the upper 20 part, the lower part being broken away and the parts being shown in idle position. Fig. 5 is the same with the parts in position for high speed. Fig. 6 is the top part of what is shown in Fig. 1 with part of the carbureter in section and showing the auxiliary air valve closed. Fig. 7 is a rear view of the means for manually closing the auxiliary air valve. Fig. 8 is a section on the line 8—8 of Fig. 5.

35 The device consists chiefly of a float chamber 10 in the shape of an ordinary bowl and a carbureting chamber 11 which is substantially U-shaped, the upper end of one side having an air intake 12 and the upper end of the other side having a mixture outlet 13 which is connected with the engine. The two parts are removably secured or screwed together.

A fuel nozzle 14 extends from the float 45 chamber into the central part of the bottom of the carbureting chamber under a point intermediate the air intake 12 and the mixture outlet 13. The fuel supply is controlled by a needle valve 15 which is secured into an extension 16 midway between the air intake 12 and the mixture outlet 13. Hence when the needle valve is screwed downward it tends to close the fuel nozzle

and when the needle valve is screwed upward it tends to open the fuel nozzle. The 55 needle valve is actuated by a crank 17 which is secured to the same above the extension 16 and extends horizontally and is pivoted at its outer end to an angular piece 18 which in turn is pivoted to a connecting bar 60 19 which is pivoted to a crank 20 on the shaft 21 of a throttle valve 22 in the mixture outlet opening. On the same end of said shaft 21 a crank 23 is secured. The action of the throttle lever is limited by a stop lug 65 24 extending laterally from the mixture outlet portion 13 of the device and as the crank 20 extends beyond the shaft 21 and carries a stop screw 25 that engages on said stop lug, the throttle is moved to a closing 70 position. When the throttle is moved to an open position, said lug stops the movement thereof by engaging the lower end of the crank 20 which is secured to the connecting bar 19. On the other side of the outlet portion 13 of the carbureting chamber the shaft 21 has a crank 26 which is pivoted to a connecting bar 27 which runs to an arm 28 which is loosely secured on a shaft 29 which extends through the air intake 12 adjacent one 75 side thereof, see Fig. 4. This shaft 29 carries an air valve 30 which is secured to said shaft at one edge thereof, as shown in Fig. 4. The air intake 12 is not circular in cross section, but rather semi-circular, as shown 80 in Figs. 2, 3 and 8. In other words, its inner surface is straight, both vertically and horizontally and it is substantially in alignment with a stop 31 in the lower part of the carbureting chamber against which the 85 lower end of the valve 30 strikes when the valve is moved to a closed position, as shown in Fig. 4. Hence the air intake is almost vertical and semi-circular in cross section and the bottom 32 is flat. The only object 90 of the peculiarity of the form of the air intake is to enable the air valve to be mounted and operated at one edge thereof and by movement of the other end of the valve to entirely open or entirely close the passageway and the fulcrum of the valve is placed above the bottom of the passageway on a higher level with the fuel nozzle so that the air valve when open, will deflect and direct 95 all of the incoming air so as to cause it to 100 sweep directly over the nozzle and over the 105

bottom of the carbureting chamber. This greatly promotes the mingling of the air and the hydro-carbon to produce a satisfactory mixture. The smaller the quantity of air admitted by the valve, the more completely it is directed against the bottom of the carbureting chamber and against and over the nozzle.

10 The crank 28 moves the shaft 29 through the intervention of a spring 128 which is secured to the shaft and coils about it with the free end pressing against the outer end of the crank 28. This provides a yielding connection between the shaft 29 and arm 28.

15 The arms and connecting bars control the various valves, air intake, throttle and fuel valve, so that the throttle lever operates and controls all of them and their operations, their opening and closing movements, are in 20 exact and predetermined relative ratios. They are arranged so that they can be adjusted with reference to the valve seats and with reference to each other. Thus the needle valve has a screw head to receive a 25 screw tightener whereby it can be adjusted and the position of the arm 17 thereon can be changed by slightly loosening the end of the arm and then tightening it. The same thing is true of the arm 28 on the shaft of 30 the air valve. There is further adjustment provided for this air valve.

35 A lever 50 is secured on the shaft 29 and extends both upwardly and downwardly therefrom so that means may be connected with either end to give it a slight oscillatory movement in the direction indicated by the arrow in Fig. 6. It is provided with an adjustable screw stop 51 for engaging the arm 28 and limiting the return movement 40 of the latter.

45 In cold weather or in any other emergency calling for especially difficult work on the part of the carbureter in starting, after the throttle lever 23 is actuated so as to partly open the throttle valve, the lever 50 is actuated in the direction of the arrow so as to at the same time close the valve 30 and cause the carbureter to draw heavily on the fuel supply for starting purposes. After the engine 50 has started, then the lever 50 can be released and thereafter the device operated as heretofore explained.

55 Thus it may be seen that the lever 23 may actuate the valve 30 only through the spring 128, that is, by increasing or decreasing its tension, and since the spring is under tension at all times, there can be no loose movement of the valve 30. A movement of the lever 50 in the direction of the arrow, see 60 Fig. 6, when the valves 22 and 30 are both open, will close the valve 30. This will increase the tension of the spring 128; and when the lever 50 is released, the valve 30 will be opened by the action of the spring 65 on the valve stem 29.

The throttle valve 22 has a small V-shaped notch on one side, as shown in Fig. 2, to unbalance it slightly and assist in starting the mixture on that side of the valve and thus allow a longer passage of the air over the 70 fuel in the lower part of the carbureter chamber.

We claim as our invention:

1. A carbureter including a carbureting chamber which is substantially U-shaped 75 and has an air intake and a mixture outlet, an air intake valve, a throttle valve, a shaft on which each of said valves is mounted and extending outward beyond the carbureting chamber, arms secured to each of said valves, 80 a bar connecting said arms, a fuel nozzle entering the lower part of the carbureting chamber, a valve extending through the top of the carbureting chamber between the air intake and mixture outlet and projecting 85 down to the nozzle, an arm on the upper end of said valve, another arm on the shaft of the throttle valve, means for pivotally connecting said two last mentioned arms, and a throttle lever on the shaft of the throttle 90 valve.

2. A carbureter including a carbureting chamber having an air intake and mixture outlet, a fuel nozzle in the carbureting chamber between the air intake and mixture outlet, a throttle valve in the mixture outlet, a valve for controlling the air intake which is secured to a shaft extending through and outwardly beyond said carbureting chamber, an arm loosely mounted on said shaft, a connection between said arm and the throttle valve whereby the two will be simultaneously operated, and a yielding connection between 95 said arm and shaft.

3. A carbureter including a carbureting chamber having an air intake and mixture outlet, a fuel nozzle in the carbureting chamber between the air intake and mixture outlet, a throttle valve in the mixture outlet, a valve for controlling the air intake, a connection between said two valves whereby they will be simultaneously operated, and means for temporarily closing said air intake valve after the throttle has been operated.

4. A carbureter including a carbureting chamber having an air intake and mixture outlet, a fuel nozzle in the carbureting chamber between the air intake and mixture outlet, a throttle valve in the mixture outlet, a valve for controlling the air intake which is secured to a shaft extending through and outwardly beyond said carbureting chamber, an arm loosely mounted on said shaft, a connection between said arm and the throttle valve whereby the two will be simultaneously operated, a yielding connection between said arm and shaft, and a lever secured to said shaft for actuating it independently of said arm or throttle valve.

5. A carbureter including a carbureting chamber having an air intake and mixture outlet, a fuel nozzle in the carbureting chamber, between the air intake and mixture outlet, a throttle valve in the mixture outlet, a valve for controlling the air intake which is secured to a shaft extending through and outwardly beyond said carbureting chamber, an arm loosely mounted on said shaft, a connection between said arm and the throttle valve whereby the two will be simultaneously operated, a yielding connection between said arm and shaft, and means for adjusting the relation between said lever and 10 arm to predetermine the position of the air intake valve.

In witness whereof, we have hereunto affixed our signatures in the presence of the witnesses herein named.
